(57) CLAIM

The ornamental design for a pet litter box, as shown and described.

DESCRIPTION

FIG. 1 is a top front perspective view of a pet litter box illustrating our new design,
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom view thereof;
FIG. 8 shows a state of use from the top, front, right side perspective view thereof;
FIG. 9 shows a state of use from the top, front, right side perspective view thereof; and,
FIG. 10 shows a state of use from the top, front, right side perspective view thereof.
The broken lines in the drawings depict portions of the pet litter box that form no part of the claimed design.

1 Claim, 10 Drawing Sheets
